Des. 171

Wm P. Cresson, David Stuart & Jacob Bresley, Philadelphia Co. Penn,
Letters Patent No. 171, dated 28th. March. 1848.
(assigned to Cresson)

The Schedule referred to in these Letters Patent and making
part of the same:

To all whom it may concern:

Be it known that we, Wm P. Cresson, David Stuart & Jacob Bresley
all of the County of Philadelphia in the State of Pennsylvania have
invented or produced a new and useful ornamental Design for
a Base for a Cannon Stove and do hereby declare that the following
is a full and exact description of the same.

Fig. 1 is the hearth or bottom plate. The form of it is a square
plate with extended corners ornamented round with a peculiar
ornament as represented at a a a a, with an extention in front

which is used as a hearth for the stove and is ornamented with a succession of scroll and shell work as represented at b, b, b, b, b, b, b, b, b.

Fig. 2. is the side plate it is ornamented with a larger panel in the centre formed of scroll and shell work as represented at a a a the top and bottom of this plate are ornamented with a waisted moulding as represented b b

Fig. 3. is the drawer front it is ornamented in the centre with flower and shell work as represented at a a a and is ornamented all around with a waisted moulding forming a panel of the whole plate as represented at b, b, b, b.

Fig. 4 is the top plate of the Base it is a square plate with extended corners and is ornamented all around the edges with the same peculiar ornament as Fig. 1 as at a a a a each corner receded back a short distance is also placed a single flower as represented at b b b b. the base of the collar intended to receive the column or cannon body is ornamented with a loope work carved against the base of the collar and as the looping approaches each flower near the corner is carved a succession of points as at c. c. c. c

Fig. 5 represents a top ring intended to be placed on the cannon body it is ornamented around the edge with a succession of scroll and leaf work represented at a a a a the centre is intended to have a larger hole or vacant space in it, this space is ornamented around the edges with a succession of balls and points as at b b b b

Fig. 6 is a round plate intended to cover the open spaces in the centre of Fig. 5, it is ornamented in the centre with a rose as at a from which are 5 nodes or spears laid out towards the edge of the plate and 5 ridges extending a wreath of flowers as at b b b

We have thus described the ornamental design which we wish to patent and do hereby claim the exclusive right
